UNITED STATES PATENT OFFICE.

CHARLES G. McCaulley, of Washington, District of Columbia.

ADJUSTABLE RAIL-BRACE.

1,312,264.

Specification of Letters Patent. Patented Aug. 5, 1919.

Application filed September 6, 1918. Serial No. 252,940.

To all whom it may concern:

Be it known that I, CHARLES G. McCaulley, a citizen of the United States, residing at Washington, in the District of Columbia, have invented certain new and useful Improvements in Adjustable Rail-Braces; and I do hereby declare the following to be a full, clear, and exact description of the invention, such as will enable others skilled in the art to which it appertains to make and use the same.

My invention relates to railway rails, but more particularly to rail-braces or side supports for rails, and it has for an object to provide adjustable braces or rail supports of novel construction for use more especially at the intersection of switch points, and upon curves to prevent spreading of the tracks, also to readily compensate for wear upon the inner side of rail heads, and for any variations in gage which may result from climatic changes or other conditions.

The invention will be hereinafter particularly described and then pointed out by the appended claims.

In the accompanying drawings which form part of this application for Letters Patent, and whereon like numerals indicate corresponding parts in the several views:

Figure 1 is a perspective view of the present invention in operative position the rail being shown in section, and

Fig. 2 is a horizontal central sectional view taken through one rail and its supporting brace.

Reference being had to the drawings and numerals thereon 1 indicates an underlying railway tie, and 2 an ordinary surmounting tie-plate bolted thereto, the latter having at one side a raised abutment 3 against which the foot 4 of rail 5 rests.

Securely bolted or riveted to the plate 2, a proper distance to one side of rail 5, is an uprising and forwardly curved bracket 6 preferably of malleable iron, and recessed or paneled as at 7 for purposes of reducing weight, the inner face of this bracket being configured by an arcuate recess 8 as shown by Fig. 2.

Fitted loosely within said arcuate recess 8 is an independent uprising forwardly curved chair 9 forming an abutting-joint with said recess in which it is thus permitted to rock horizontally. The opposite edge or

face of said chair 9 is straight as shown at 10, but grooved horizontally throughout its length as shown at 11, Fig. 1.

Slidably resting within the aforesaid horizontal groove 11 is a flange or tongue 12 projecting from the rear of a rail-supporting block 13, and perforated near one end by a series of cotter-pin holes 14 arranged substantially as shown and for the purpose of receiving a locking pin 15 as will later appear. The face of this supporting block, as also the edge of its tongue 12, is of wedge formation, as most clearly indicated at 16, Fig. 2, while its forwardly projecting edges 17 find bearings directly upon the rail 5, preferably beneath the head and above the foot thereof, as shown.

This being a description of my invention in one form of embodiment, it should be understood that the several component parts of the structure shown and described may be variously modified, changed and rearranged without departing from the spirit of the present invention as hereinafter claimed. For example, it is entirely feasible to omit the interposed chair 9 forming the wedge groove 11 in the face of bracket 6 to directly receive flange 12 when wedged or driven in between said bracket and the rail 5.

Having thus described my invention, its use and operation may be briefly stated as follows:

The relative position of a railway tie, tie-plate, rail 5, and bracket 6 being substantially as shown, the convex surface of the horizontally grooved chair 9 is next positioned within the concavity of said bracket 6, thus providing for a degree of horizontal adjustment between these elements. The wedge-shaped supporting block 13 with its projecting tongue 12, running in the groove 11, is then driven firmly between chair 9 and rail 5 until the foot 4 of the latter is forced and retained securely in contact with abutment 3 upon the tie-plate, whereupon a cotter pin 15, or other form of locking pin, is introduced into the last of the exposed pin holes 14 to retain all parts in their proper adjusted position. And, because of the succession of said pin holes 14, it is apparent that subsequent and further adjustment of the rail brace may readily be effected when rendered necessary or desirable because of

wear and tear upon the parts in service, or because of expansion and contraction occasioned by climatic conditions.

It will be noted also that the abutting joint of special construction, or concavo convex relation of bracket 6 and chair 9, always insures a perfectly uniform and parallel engagement of rail 5 by the edges 17 of the supporting block 13, regardless of the relative position of tie-plate and tie and regardless of whether or not the tie passes beneath the rails exactly at right angles. Obviously, this feature of the present invention greatly facilitates installation of the braces, and particularly when working upon curves in the road, and when the ties are more or less irregular in shape.

Having thus described my present invention, what I now claim and desire to secure 20 by Letters Patent is:

1. In an adjustable rail brace the combination with a bracketed tie plate, of a rail-supporting block having a projecting tongue of wedge formation throughout its entire 25 length perforated by a succession of locking holes and adapted to be driven through said bracket, and a locking pin for engaging one of said holes to retain the supporting block in adjusted positions with relation to the 30 bracket aforesaid.
2. In an adjustable rail brace the combi-

nation with a tie plate, of a horizontally rotatable chair adjacent to said bracket, a rail-supporting block of wedge formation adapted to be forced past said chair and 35 bracket elements, and means for locking said supporting block in adjusted positions with relation to the chair and bracket aforesaid.

3. In an adjustable rail brace, the combination with a tie plate having a concave 40 face, a horizontally rotatable chair having a convex surface fitting the concavity of the bracket aforesaid, a rail-supporting block of wedge formation adapted to be driven past said chair and bracket elements, and 45 means for locking said supporting block in adjusted positions.

4. In an adjustable rail brace the combination with a tie plate of a horizontally rotatable chair connected with said bracket 50 by an abutting joint and having a horizontal groove therein, a rail-supporting block of wedge formation having a tongue slidably positioned in the groove aforesaid, and means for locking said supporting block in 55 adjusted positions.

In testimony whereof I affix my signature in presence of two subscribing witnesses.

CHARLES G. McC AULLEY.
